UNITED STATES PATENT OFFICE.

CARL R. LINDENBERG, OF COLUMBUS, OHIO, ASSIGNOR TO THE M. C. LILLEY & COMPANY, A CORPORATION OF OHIO.

LEGGING.

1,284,386.

Specification of Letters Patent. Patented Nov. 12, 1918.

Application filed February 1, 1918. Serial No. 214,800.

To all whom it may concern:

Be it known that I, CARL R. LINDENBERG, a citizen of the United States, residing at Columbus, in the county of Franklin and State of Ohio, have invented certain new and useful Improvements in Leggings, of which the following is a specification.

This invention relates to leggings and has for its primary object to provide a legging 10 wherein is employed improved features of construction for stiffening or reinforcing the marginal edges thereof, whereby when the legging is applied, the same will present a neat and pleasing appearance and to effectively preclude bulging or buckling of said edges.

With these and other objects in view, the invention accordingly consists in the novel features of construction, combination of elements and arrangement of parts hereinafter 20 fully described and having the scope thereof defined by the claims hereunto appended.

In the drawing, wherein has been shown the preferred embodiment of the invention:

Figure 1 is a front elevation of a legging constructed in accordance with the principles of the invention.

Fig. 2 is a vertical sectional view taken 30 along the line 2—2 of Fig. 1.

Fig. 3 is a detailed perspective view of the metallic member employed for stiffening the legging and

Fig. 4 is a horizontal sectional view taken 35 through the legging and disclosing the latter in a buckled position.

Similar characters of reference denote corresponding parts throughout the several views of the drawing.

Referring more particularly to the drawing, the legging 1 comprising the present invention is preferably formed from leather, although it will be understood that any other desirable material may be employed in lieu 40 of the material described. In this instance the body of the legging is formed of superposed sections so as to provide a body portion of suitable thickness and durability, and said superposed sections are retained in position by stitching the marginal edges of the legging as indicated by the numeral 2.

In order to provide an improved method of stiffening the front edge 3 of the legging so as to prevent the latter when buckled 55 from assuming a wrinkled or bulging con-

dition, use is made of a metallic stiffening member 4. The latter is situated within the superposed parts or sections of the legging at a position adjacent to the edge 3 and is formed to provide a vertically extending shank portion 5, which portion is secured in position through the medium of rivets 6, passing through the sections of the legging and through openings 7 formed in the shank 5. This construction provides a substantial 60 and effective method of retaining the member 4 in its operative position within said legging.

The lower extremity of the shank 5 terminates in a tongue portion 8, which latter is extended beyond the rear face of that portion of the legging adjacent to the edge 3, and is adapted to engage with a socket element 9 carried by the opposite edge portion 10 of the legging 1. Thus in order to secure 70 the lower portion of the legging about the limb of the wearer, the edge portion 3 is pulled so as to overlap the adjacent portion 10, and this will permit the tongue 8 to enter the socket 9, whereby a convenient and positive method is provided for retaining the lower portions of the legging in overlapped and secured relation.

The upper extremities of the legging are secured by providing the portion 3 with a plurality of vertically extending openings or slots 11, either of which slots being adapted to receive a staple 12, carried by the legging portion 10. This staple is retained in position through the agency of a leather strip 13, which is sewed or otherwise secured to the portion 10, and overlaps the base 14 of the staple so as to maintain the latter in a relatively rigid position. It will be seen that by passing the staple 12 through either 85 of the openings 11, that the sections or portions 3 and 10 of the legging will be drawn into overlapped relation, and this condition is maintained through the position of a strap 15 which is secured to the portion 3 90 and is adapted to be passed through the eye portion of the staple 12 which protrudes beyond the openings 11, thus providing a simple and effective method of quickly and conveniently securing the upper overlapping 95 portions of the legging. The end of the strap 15 is passed through a loop 16, carried by the strip 13, and is thus retained in a secured position. The plurality of openings or slots 11 are provided in order that rela- 100 105 110

tive adjustments of the portions 3 and 10 may be effected, so that the legging may be adapted to different persons.

Hitherto considerable difficulty has been 5 encountered in preventing that portion of the edge 3 which is located adjacent to the slots 11 from bulging or buckling, and in order to provide means whereby this objectionable feature will be obviated, the stiffening 10 member 4 has the shank 5 thereof extended at its upper end to produce a widened, substantially rectangular portion 17, which portion is provided with a squared opening 18. The latter is so located that it will aline 15 with the slots 11, so as to permit of the insertion of the staple 12 therethrough. However, due to the rectangular formation of the portion 19, the latter will surround said 20 slots and will effectively prevent that portion of the legging adjacent thereto from bending or wrinkling, as will be clearly understood.

From the foregoing it will be seen that there is provided improved means for connecting the overlapping portions of the legging and through the application of the stiffening member 4, the outer edge 3 of the legging will constantly be maintained in a neat, presentable and trim condition by 25 eliminating the bending or flexing of the legging parts adjacent thereto.

Having described the invention, what is claimed is:

1. A legging comprising a body portion 35 terminating in overlapping securing edges, means for securing the upper portions of said edges in fastened relation, including a staple member fixed to the under edge of

said legging, said staple member being adapted to pass through any one of a plurality of slots formed in the outer edge, a strap carried by said outer edge and adapted to be inserted through that portion of the staple which protrudes beyond said slots, and a stiffening member vertically positioned within said outer edge and having a portion thereof situated to surround the slots formed in said outer edge. 40 45

2. A legging comprising a body portion formed to terminate at the front thereof in overlapping under and outer edge portions, means for securing the upper parts of said overlapping edge portions in fastened relation, consisting of a staple member carried by said under edge portion, said staple member being adapted to pass through a slot formed in the outer edge portion, a strap adapted to be inserted through said staple when the latter is positioned within said slot, a metallic stiffening member vertically positioned within said legging and formed to lie parallel with said outer edge portion, said stiffening member terminating at its upper end in a relatively widened portion in which is formed an opening, the latter opening being arranged in alinement with the slot formed in said outer edge portion, and a tongue formed upon the lower end of said stiffening member for engagement with a socket element carried by the lower extremity of said under edge portion, whereby the lower parts of said legging may be secured together. 50 55 60 65 70

In testimony whereof I affix my signature.

CARL R. LINDBERG.
